UNITED STATES PATENT OFFICE.

JOHN D. EHRLICH, OF BERWICK, LOUISIANA.

PROTECTION OF VESSELS AGAINST TORPEDOES AND MINES.

1,253,017.

Specification of Letters Patent.

Patented Jan. 8, 1918.

Application filed June 12, 1917. Serial No. 174,298.

To all whom it may concern:

Be it known that I, JOHN D. EHRLICH, a citizen of the United States, residing at Berwick, in the parish of Saint Mary and State of Louisiana, have invented certain new and useful Improvements in Protection of Vessels Against Torpedoes and Mines; and I do hereby declare the following to be a full, clear, and exact description of the invention, such as will enable others skilled in the art to which it appertains to make and use the same.

The present invention relates to improvements in guards for intercepting torpedoes and floating mines from ships, and has for one object to provide an improved guard of this character which will be composed of a series of units adapted to be lowered to an operative position spaced from the side of a ship where such units will prevent the passage of torpedoes or floating mines to the ship; said units being hingedly supported from the side of the ship and being connected to means for raising and folding the same up against the side of the ship above the water line to an inoperative position where they will not impede the progress of the ship through the water.

Another object of the present invention resides in providing a guard for ships which, when in the lowered operative position will be held locked against accidental displacement, but which allows of the guard being drawn up readily to the inoperative position when its use is not required.

In the accompanying drawings forming a part of this application, and in which similar reference symbols indicate corresponding parts in the several views:

Figure 1 is a fragmentary side elevational view of a ship shown equipped with a torpedo guard constructed in accordance with the present invention.

Fig. 2 is a fragmentary cross sectional view through one wall of a ship and illustrating the improved guard as attached thereto and occupying the operative position.

Fig. 3 is a similar view indicating the guard in partially raised position.

Fig. 4 is a fragmentary perspective view of a ship illustrating two of the guard units, one being in the operative and the other in the inoperative position; and

Fig. 5 is a fragmentary elevational view of one of the guard units.

Referring more particularly to the drawings, wherein one embodiment of the present invention is illustrated, 1 designates the side and 2 the deck of a ship to which my improved guard is attached.

The guard is composed of a series of frames 3 mounted side by side in close relation, and being supported from the side 1 of the ship by upper and lower pairs of arms 4 and 5. The upper arms 4 are hinged to the side 1 of the ship, as indicated at 6; while the lower series of arms 5 are similarly attached to the side 1 of the ship by hinges 7. Hinged connections 8 and 9 are made between the arms 4 and 5 and the respective frames 3 which they support.

Through the supporting arms 4 and 5 the several frames 3 are adapted to be raised and folded against the side 1 of the ship, and for this purpose any suitable means may be employed, one of such means being illustrated by the chains 10. Each chain is connected at its lower end to a frame 3, as shown at 11, and is carried upwardly therefrom over the deck 2 of the ship, at which point it may pass over a pulley 12. The chain 10 may be drawn up by hand or suitable power apparatus, as desired.

As clearly shown in Figs. 2, 3 and 4, the chains 10 are directed beneath the rods 13 which are connected at their opposite ends to, and form toggle centers for pairs of braces 14 and 15 connected between the ship's side 1, as shown at 16, and the upper series of arms 4, as indicated at 17. These braces 14 and 15, at their inner ends, carry shoulders 18 and 19 which are adapted to abut together when the frames 3 are in the lowermost position illustrated in Fig. 2, and which have the effect of locking said frames in the operative position and preventing same from being accidentally displaced upward, as by force of the waves or the impact of a torpedo or floating mine.

The abutting shoulders 18 and 19 of the braces 14 and 15, however, do not affect the raising of the guard sections from the operative to the inoperative position by the chains 10, as such chains when drawn taut will first engage the rods 13 and break the toggle joint, as shown in Fig. 3; after which the continued hauling of the chains 10 will raise the frames 3 up against the ship's side 1, where they will be clear of the water.

The frames 3 may be constructed in any suitable manner to engage the torpedoes and

floating mines and preventing them from getting to the wall of the ship, and preferably with a view to preventing the firing of the torpedo or mine; and for this purpose it will be found advantageous to employ the construction shown more particularly in Figs. 4 and 5; wherein longitudinal and transverse strands 20 and 21 of rope, wire, or other suitable material are stretched across the frames 3 and are connected to the longitudinal and side rails of said frames by coil springs or other resilient connections 22 and 23.

It is the aim of providing these resilient connections 22 and 23 that the externally yielding structure resulting therefrom will not offer that rigidity to the firing pin of the torpedo which will be necessary to explode the same; but which will readily yield if encountered by the torpedo.

In use, the guard sections will be arranged all around the ship, and will be normally carried in the position shown to the right in Fig. 4, where they are collapsed against the side 1 of the ship and extend well above the water line, so as not to impede the progress of the ship through the water. When, however, the ship enters the danger zone, the chains 10 may be released and the guards 3 will either fall by gravity of their own weight or may be forced down to the operative position shown to the left in Fig. 4 and also in Figs. 1 and 2 where they will extend for a considerable distance below the surface of the water, and preferably for a slight distance below the bottom line of the ship; in which position they will form an effective barrier to torpedoes and floating mines. When lowered, the braces 14 and 15 will assume the position shown in Fig. 2, with the shoulders 18 and 19 brought together so that any external force applied to the guard sections 3 will be ineffectual to displace such guard sections from the lowered position shown in this figure.

After the danger zone has been passed, the several guard sections 3 can be readily raised to the inoperative position, which will allow the ship to proceed at full speed without interference, by hauling in the chains 10, which will initially break the toggle joint by raising the rods 13 and subsequently will draw the guard sections 3 to the inoperative position above the water line.

If desired, only certain of said guard sections 3 may be lowered, and the fact that such guard is made up of relatively small sections or units, enables the same to be readily and quickly shifted from the raised to the operative position.

Braces 25 are connected diagonally between the ship's side 1 and the guard units; such braces being attached preferably by universal joints 26 and 27. The braces 25 are of value in preventing horizontal dis-

placement of the guard frames 3 when the ship is in motion by reason of the great resistance to their passage offered by the water.

It is obvious that those skilled in the art may vary the details of construction and arrangements of parts without departing from the spirit of my invention, and therefore I do not wish to be limited to such features except as may be required by the claims.

I claim:

1. A device of the character described including guard means movable to and from an operative and an inoperative position, means for shifting said guard means, and means unlocked by said guard-shifting means for holding said guard means against accidental displacement from the operative position, substantially as described.

2. A device of the character described including guard units, arms hinged between the ship and said units for holding the latter in an operative position spaced from the ship, means for locking said units in the operative position, and means both for unlocking said locking means and for raising said units against the ship and above the water line, substantially as described.

3. A protector for ships including guard means, supporting means adapted to hold said guard means in an operative or inoperative position, braces for locking said guard means in the operative position, a rod forming a toggle center for said braces, and means for raising the guard means from the operative to the inoperative position and adapted to pass under said rod to first break the toggle joint when a lifting force is applied, substantially as described.

4. A protector for ships including a series of units, hinged arms supporting said units, pairs of braces having shoulders adapted to abut and lock the units in an operative position, rods forming the toggle centers for said braces, and means for hoisting said units passing beneath said rods to first break the toggle joint when a lifting pull is applied, substantially as described.

5. A device as described including a series of guard units, arms connecting said units to be folded close against a ship's side above the water line or carried in spaced relation thereto in a position to intercept torpedoes, braces arranged in pairs for locking said units in the latter-mentioned position, rods connecting adjacent pairs of braces and forming a toggle center therefor, and means for hoisting said units passing beneath said rods and being adapted when pulled upon to initially break the toggle joint, substantially as described.

6. A protective device for ships which consists in a series of guard units arranged about the ship, arms hinged to the ship and to said guard units and adapted to carry the

units in either an inoperative position folded close against the ship's side above the water line or an operative position extended out from the ship and projecting below the surface to intercept torpedoes, diagonal braces having universal joint connections for said units, pairs of braces for locking said units in the operative position, rods connecting

said braces and forming toggle centers for same, and means for raising said units passing beneath said rods to first break the toggle joint when a hoisting force is applied, substantially as described. 10

In testimony whereof, I affix my signature.

JOHN D. EHRLICH.
